UNITED STATES PATENT OFFICE.

ALLAN C. RUSH, OF LOS ANGELES, CALIFORNIA.

DEEP-WATER BRIDGE-PIER AND MEANS FOR AND METHOD OF CONSTRUCTING THE SAME.

1,079,517.

Specification of Letters Patent.

Patented Nov. 25, 1913.

Application filed August 30, 1911. Serial No. 646,929.

To all whom it may concern:

Be it known that I, ALLAN C. RUSH, a citizen of the United States, residing at Los Angeles, in the county of Los Angeles and State of California, have invented a new and useful Deep-Water Bridge-Pier and Means for and Method of Constructing the Same, of which the following is a specification.

10 The object of this invention is to make provision whereby bridge piers may be constructed in deep water subject to currents and heavy water pressure.

An immediate object of this invention is 15 to make provision whereby a suspension bridge between the cities of San Francisco and Oakland, California, can be provided with intermediate supporting piers.

A depth at which some of such piers must 20 be constructed in the water is as great as 120 feet with a probable depth of 150 feet below high tide to bed-rock. In this water swift currents run for the major portion of every twenty-four hours, the currents being 25 neutralized at times by the meeting of the inflowing tide and the outflowing river. The static pressure of the water at the depth of 120 feet is estimated at 7689.6 pounds per square foot and it has heretofore been 30 considered impossible to construct the piers necessary for the service above stated. I propose to overcome the difficulty by constructing a suitable reinforced concrete structure as a float in a dock and then to 35 tow the structure which I term a pier frame, to the site where the pier is to be stationed, and then to seat the pier frame on such site; provision being made whereby the pier frame may during the process of construction 40 have sufficient buoyancy for the purpose, and further provision being made whereby such buoyancy can be eliminated when the pier frame is properly stationed, and to complete the pier by filling the frame, 45 thus giving permanency and solidity to the pier sufficient to fill the requirements.

It is an object also to make provision 50 whereby workmen may, if necessary, operate at the bed of the body of water for the purpose of clearing said bed of obstructions or for leveling the pier frame or for such other purposes as may be required during the operation of fixing the pier on its site.

I shall herein illustrate and describe the 55 invention in the form at present deemed

most practical, but it is to be understood that various changes and modifications within the judgment of the constructor may be made without departing from the broad spirit of this invention.

An object of the invention is to so construct the pier that it will be storm proof; also to give workmen opportunity to work on the bed of the bay or other body of water at the pier site to clear or excavate the same.

It is understood that the invention may be applied for building piers for any purpose wherever the conditions may make it necessary or desirable.

Referring to the accompanying drawings:—Figure 1 is a plan of the completed pier frame in a dry dock after the water has been let into said dock; barges being in position ready for towing the pier frame out to its site. Fig. 2 is a side elevation of the buoyant reinforced concrete pier frame as the same would appear after completion at the dock. Fig. 3 is an end elevation of the pier frame shown in Figs. 1 and 2. Fig. 4 is a fragmental plan of the pier frame showing one cap in place, the other caps having not been applied to the tubes, or having been removed therefrom. Fig. 5 is a fragmental vertical section of a tube with cap in place. Fragments of adjoining tubes are also shown. Fig. 6 is a longitudinal sectional elevation of the pier frame through a row of tubes showing the pier frame fully constructed. Fig. 7 is a side elevation of the pier frame and barges afloat in the dock. Fig. 8 is an end view of the pier frame and barges afloat. Fig. 9 is a transverse vertical section through a transverse row of tubes showing the pier frame in place above its site before the mud has been removed in preparation for receiving the final concrete filling. Fig. 10 is a view analogous to Fig. 9 showing the pier completed ready to receive the superstructure.

From the nature of the views proportions have not been preserved throughout and the proportions may be varied within the judgment of the constructor.

The pier illustrated in the drawings is designed to be 325 feet long by 225 feet wide at the base and 150 feet high, and it is to be understood that the sizes and proportions may be varied in accordance with the requirements for the various piers. It has an

internal tubular structure and a concrete body and an arched base all of which will now be particularly described.

The bottom plate 1 may be constructed wholly or in part of steel or iron and may or may not have a central base concavity 2 which in the instance shown forms an arch having a height of 12 feet at its spring, said plate forming around said arch a practically level border 3 having a width of 25 feet more or less said plate being turned to form an upstanding rim 4 entirely around the plate and of a height of about two feet. To this rim is riveted a downwardly projecting base flange 5 which may extend down a depth of about two feet, more or less below the level of the border 3. The bottom plate and its rim may be of steel plates riveted together and about an inch and a half in thickness. The base flange 5 may be of sheet iron about one-half inch thick and capable of being bent as the frame settles to conform to the unevenness of the bed rock. The plate may be laminated or may be of a single thickness as may be found the most practicable in actual construction. The arch of the base plate is perforated with openings 6 and is constructed to receive the bottoms of upright tubes 7 that are fastened by any suitable means as the angle-plates 8 riveted to the base plate and to the tubes. Said tubes may be constructed in any suitable manner of iron or steel plates not shown, riveted together in the usual manner and the adjacent walls of adjacent tubes may be riveted together and to frame plates 9 by rivets 10. Iron or steel reinforcing elements are fastened to the base plate at intervals and extend upward therefrom to hold the concrete which is to be applied in the course of construction. Some of the reinforcing elements consist of trough-shaped structures 11 which may be built of iron or steel plates or may be built of ribs or angle-iron bars and extend from the inter-tube spaces downwardly and outwardly at an angle and are united. These reinforcing elements 11 form protecting shields for the outside tubes to protect them from external pressure. The reinforcing elements 11 along the sides are fastened at their inner terminals to the cross-plates 9 that are riveted thereto and extend between the tubes and are held by the rivets 10 that hold the tubes together. Said cross-plates 9 may be fastened by angle-iron plates 13 to longitudinal plates 14 to which the elements 11 at the upper ends of the nest of tubes are riveted, so that the reinforcing elements are supported by the plates and also by the tubes, there being spaces around said elements to receive concrete. The tubes are open at the bottom and are covered at the top by heads or caps 15 each provided with a hermetically sealable man-hole 16, a compressed air port

17 and exhaust port 18. A compressed air pipe line 19 communicates through the valves 20 with the compressed air ports. The base plate, the tubes and the reinforcing elements may all be constructed of reinforced concrete or other material within the judgment of the engineer.

The method of construction is as follows:—A dry dock 21 will be provided for the pier, and the base plate will first be constructed in said dock; and upon said base plate will be fastened the tubes 7 and the reinforcing elements 11. The space outside the nest of upright tubes 7 will be filled with concrete; suitable forms, not shown, being provided to give appropriate external shape to the concrete body 23 around the nest of tubes. The pier frame will preferably be completed inside the dry dock which will be deep enough to float the pier frame when the water is let into the dock. Said dry dock will also preferably be large enough to accommodate two steady barges 22 arranged alongside of and lashed to the pier frame near the water line. As the work of putting the concrete in place progresses any reinforcing cables, rods or other elements may be applied as desired. The cables 11 wound around the slanting V-shaped trough-like reinforcing elements 11 indicate some of the reinforcing elements that may be used. No attempt has been made to illustrate all of such elements that may be found advisable. In practice the pier frame having the internal cavities as the tubes 7 and base concavity 2 will be constructed in a dry dock 21 having a sufficient depth to float the frame with the assistance of such barges 22 as may be deemed advisable by the constructing engineer, said dock being large enough to accommodate the pier frame and the barges. The pier frame will be constructed as a reinforced concrete structure provided with a nest of large empty tubes 7 sufficient to give the required buoyancy to the frame during the process of floating the frame from the dry dock to the pier site. The frame is completed outside the tubes by the concrete filling 23 that is more or less reinforced as conditions may require. The tubes are hermetically sealed at the top by the caps or heads 15 and compressed air is forced through the pipes 19 and valved ports 17, thus forcing the water down out of the tubes until the pier frame is produced giving the required buoyancy. Then the pier frame is lashed to the barges and will be towed to the site where the pier is to be located and may there be secured by hawsers and anchors, not shown, and the compressed air allowed to escape from the tubes through the valved exhaust ports 18 provided for that purpose. When the pier frame has been lowered to the bed of the body of water, if there is a mud or earth deposit 24 on the bed-rock the

frame may be allowed to settle down into such comparatively soft deposit so that such deposit will fill the concavity underneath the pier frame and may squeeze up into the tubes. The compressed air may be let out of such ones of the tubes and in such a manner as to preserve the level of the top of the pier as it settles down and the work proceeds and one or more man-holes 16 may be opened to admit machinery and workmen into one or more of the tubes for the purpose of clearing out the mud or other material that may be reached therethrough. Interior bulkheads indicated at 25 and of any usual structure will be provided if it is desired to work in any such deposit under pressure higher than atmospheric pressure, but it is assumed that ordinarily such bulkheads will not be required for the reason that the air pressure applied through some of the tubes may force the mud up in one or more other tubes so that it may be readily gotten at and removed. When the material has been excavated to the bottom of a tube excavations underneath the base plate may be conducted; bulkheads being used if necessary to maintain pressure in excess of atmospheric pressure during the said excavation. It may be found desirable to make anchor receiving excavations 27 in the bed-rock. The downwardly extending flange 5, as it comes into contact with irregularities of the bed-rock may be bent by the weight of the settling pier frame to conform to the surface of the bed-rock so as to exclude to a large degree the entrance of mud or sand from outside of the pier frame. It is intended that the tubes shall have sufficient area so by increasing the air pressure in appropriate tubes at one side or at one end while the air pressure is released from the tubes at the other side or from the other end to allow the top surface of the pier to be kept level, especially when the pier is to be finally seated. If it should be found that the bed-rock does not properly conform to the border 3 around the arch of the base, said bed-rock may be excavated in places and built up by concrete in other places as may be required, so that when the pier is finally seated it will rest upon a solid foundation to which it conforms. When the border has thus been seated the cavities at the foundation and under the base plate may be filled with concrete, and before this is completed anchor irons 28 may be inserted into the anchor excavations 27 and afterward built and extended up through the tubes 7 to the top of the pier frame to afford the necessary anchorage for the superstructure. Then the tubes may be partly or completely filled with concrete, and the pier will thus be completed. The pier thus provided may then be extended up indefinitely above the water level as a reinforced concrete structure upon which may be founded any

desirable form of bridge or other superstructure.

It is intended to place the pier frames with their greatest length transverse the bridge and the ends of the piers are pointed to deflect the tides and currents that sweep through the channel or bay.

By constructing the pier frame of reinforced concrete having the central nest of tubes 7 and reinforcing elements 11 and 75 maintaining air pressure therein until the pier frame is at the pier site and then maintaining internal pressure either by the admitted water or by compressed air, all danger of collapsing the frame is absolutely 80 eliminated and furthermore the reinforced concrete structure around and internally supported by the nest of tubes can be made of such strength as to avoid any possibility of collapsing under any pressure to which 85 the structure can be subjected.

I claim:—

1. The method set forth of constructing a deep water pier which consists in first constructing in a dry dock a reinforced concrete 90 pier frame having internal cavities; admitting water to the dry dock and excluding it from all or a portion of said cavities sufficiently to give required buoyancy for floating the pier frame; then towing the pier 95 frame to the pier site; admitting water to the cavities and lowering the pier frame onto the site; excavating the mud or other material in said cavities and allowing the pier to settle into place.

2. The method set forth of constructing a deep water pier which consists in first constructing in a dry dock a reinforced concrete pier frame having internal cavities; admitting water to the dry dock; forcing compressed air into the cavities and thereby excluding water from all or a portion of said 105 cavities, giving required buoyancy for floating the pier frame; then towing the pier frame to the pier site; lowering the pier 110 frame onto the site, excavating from said cavities the mud or other material from therein, allowing the air to escape and the pier to settle into place; and filling the cavities with concrete.

3. The method set forth of constructing a deep water pier which consists in first constructing in a dry dock a reinforced concrete pier frame having internal cavities; admitting water to the dry dock and excluding it from all or a portion of said cavities sufficiently to give required buoyancy for floating the pier frame; then towing the pier frame to the pier site; lowering the pier 120 frame onto the site; excavating from said cavities the mud or other material therein; allowing the pier to settle into place; making anchor-receiving excavations in the site and filling said excavations and the cavities with concrete.

4. The pier frame substantially set forth comprising a nest of tubes; frame plates between and fastened to adjacent tubes; and a reinforced concrete body around the nest.
5. The pier frame substantially as set forth comprising a nest of tubes, and trough shaped reinforcements and a reinforced concrete body around the nest.
6. The pier frame substantially as set forth comprising a tubular interior structure and a reinforced concrete body around said interior structure, there being an arched base plate at the bottom.
7. A pier frame comprising an internal tubular structure, an arched base and a concrete body on the base and around the structure.
8. A pier frame comprising an internal tubular structure, an arched base and a reinforced concrete body on the base and around the structure.
9. A pier frame having an internal tubular structure, an external concrete body, and an arched base having an approximately level border.
10. A pier frame having an internal tubular structure, an external concrete body, and an arched base having an approximately level border; there being a downwardly extending flange around the border.
11. A reinforced concrete pier frame having a hollow base and internal structure, and a bendable downwardly extending flange around the base.
12. A pier comprising an internal tubular structure, a concave base, a concrete body around said structure, and a concrete filling in the tubular structure and base.
13. A pier frame comprising a tubular internal structure; a concrete body around the structure; heads for the tops of the tubes and means to force compressed air into said tubes; the bottoms of the tubes being open.
14. A pier frame comprising a nest of tubes a reinforced concrete body around the tubes, and means to force compressed air into the tubes.
15. A pier frame comprising a nest of tubes a reinforced concrete body around the tubes, means to force compressed air into the tubes, and means to exhaust the compressed air from the tubes respectively.
16. A pier comprising a tubular structure, a reinforced concrete body around the structure, a filling in the tubular structure and anchors in the filling.

In testimony whereof, I have hereunto set my hand at Los Angeles, California, this 24th. day of August, 1911.

ALLAN C. RUSH.

In presence of
JAMES R. TOWNSEND,
L. BELLE RICE.
